AIR CONDITIONING SYSTEM

Samuel M. Anderson, Sharon, Mass., assignor to
B. F. Sturtevant Company, Boston, Mass.Application July 8, 1937, Serial No. 152,579
Renewed October 17, 1939

2 Claims.

(CL 98—10)

This invention relates to the conditioning of air and relates more particularly to methods and apparatus for the purification and temperature conditioning of air.

5 In most buildings and in passenger vehicles for reasons of economy, the air from the occupied space is continuously recirculated through the conditioner, the air supplied to the occupied space being made up of a small volume of fresh 10 air and a much larger volume of recirculated air. It has been determined that the coughing of one passenger in a railway passenger car, for example, adds many germs to the air in his or her vicinity, which air is recirculated through the 15 conditioner and supplied with the germs to the other passengers. The usual air conditioners especially of the dry surface or coil type as distinguished from washers, do not effectively remove bacteria from the air. Another recognized disadvantage of reconditioning recirculated air is that odors are not removed and this objection applies particularly to the use of coil type conditioners in railway passenger cars.

This invention provides means for removing 25 bacteria and odors from air and for supplying substantially pure air to a conditioner for temperature and where desired, humidity conditioning. The conditioner may be of the coil type although it is preferred that air washers be used 30 for the reason that experience has shown that not only is the air treated by such conditioners more wholesome but more accurate humidity and temperature control may be obtained.

An object of this invention is to effectively 35 purify air.

Another object of the invention is to remove bacteria from air to be conditioned.

Another object of the invention is to remove odors from air to be conditioned.

40 Another object of the invention is to provide in an air conditioning system an air purifier and conditioner.

Another and more limited object of the invention is to provide within the limited space available, an air purifier and conditioning system for a passenger vehicle.

Other objects of the invention will be apparent from the following description and the drawings:

The invention will now be described with reference to the drawings of which:

Fig. 1 is a view in section of a railway passenger car on which is installed one embodiment of the invention;

Fig. 2 is a schematic view of the system of Fig. 1, with supply accessories;

Fig. 3 is a plan view, partially in section of the system of Fig. 1;

Fig. 4 is a sectional view along the lines 4—4 of Fig. 3, and

Fig. 5 is a partial view, enlarged of the duct 5 of Fig. 4 and is taken along the lines 5—5 of Fig. 4.

Due to the necessity of avoiding using passenger space, the space for air conditioning apparatus is limited. It is customary to mount the 10 air conditioners in one end and in the roof zone of a railway car. It is usual with such arrangements to draw the recirculated air through a ceiling grille underneath the air conditioner, fresh air being drawn in through the vestibule. 15

According to this invention, it is proposed to purify the recirculated air on its way to the conditioner. The proper purifying apparatus occupies considerable space so in one embodiment of this invention, the purifier is located overhead 20 20 in the passenger space in the opposite end of the car from the air conditioner and supplies pure recirculated air to the conditioner.

It is preferred that a spray type conditioner 25 6 such as is disclosed in my copending application, Serial No. 107,019, filed Oct. 22, 1936, be mounted in one end of the car. This conditioner receives and sprays refrigerated water in summer and may contain the usual heat exchange coils for heating in winter. The fans 7 of the conditioner 6 draw in fresh air through the vestibule grille 8 containing the usual filter and supply it to the conditioner. The conditioner 6 also receives purified recirculated air for reconditioning 30 as will now be described.

35 The purifier 9 may be an electro-static precipitator of the type described beginning on page 159 of the January, 1937, Proceedings of American Institute of Electrical Engineers. With this type of purifier, microscopic foreign particles are 40 removed from the air and deposited for collection by electro-static action. The fans 10 are associated with the precipitator and draw in recirculated air from the car through the grille 11 and pass it through the purifier. 45

The ultra-violet sterilizer 12 shown mounted on the output side of the precipitator 9 may also be used for purifying the recirculated air drawn in by the fan 10. This lamp 12 may be used alone for sterilizing the air or may be used with or alternately with the precipitator as desired by manipulation of the switches 13 and 14 which act to connect the precipitator 9 and lamp 12 to the rotary converter 15 or other suitable source of electric energy. The lamp 12 may be of the type 55

which generates very strong ultra-violet light through the ionization of a gas such as mercury vapor.

As shown most clearly by Figs. 3, 4 and 5, the 5 fans 10 draw in recirculated air from the passenger space; pass it through the precipitator 9 and if the sterilizer 12 is used, over it, and then discharge the purified air through the duct 16 which extends the length of the car into the 10 chamber 17 enclosing the conditioner 6 and fans 7. The fans 7 draw in outside air through the grille 8 and the mixed outside and the purified 15 recirculated air is passed through the conditioner 6 where it is conditioned.

15 The conditioned air from the conditioner 6 is forced through the duct 18 and discharges therefrom through the small openings 19 into the passage 24 from which it passes into the passenger space through the openings 20 below the deflector 21. The ducts 16 and 18 may be arranged alongside each other thereby conserving both space and material.

Means may be provided of course for passing some outside air into the purifier and means may 25 also be provided for passing some recirculated air directly into the conditioner. Likewise the purifier could discharge air directly into the car. It is preferred however, that the air supplied to the purifier be all recirculated air which is more likely 30 to be contaminated by odors and germs and that the conditioner handle directly introduced outside air when is likely to be substantially free from contamination. With the arrangement illustrated, all foreign matter added within the car 35 to the air is removed with the result that the savings in refrigeration due to the reconditioning of recirculated air are accomplished, while pure air is supplied to the conditioner. The precipitator 9 removes the small oily particles responsible for odors as well as a large percentage of the 40 bacteria. During an epidemic or when it is desired to take unusual precautions, the ultra-violet lamp 12 may be used with the precipitator 9. The ultra-violet lamp is believed to be more effective 45 as far as destroying germs is concerned since its light acts upon invisible germs, the minute size of which might prevent them being acted upon by the electro-static precipitator. Of course the ul-

tra-violet lamp could be mounted in advance with respect to air flow of the precipitator.

In the arrangement illustrated by the drawings, the fans mounted with the electric purifier are not absolutely necessary as the fans of the conditioner will draw the recirculated air through the sterilizer.

The sterilizer as well as the conditioner may, of course, be located elsewhere in or on the car than overhead the passenger space.

10 While one embodiment of the invention has been described for the purpose of illustration, it should be understood that the invention is not limited to the exact apparatus and arrangement illustrated as many departures may be suggested 15 by those skilled in the art without departing from the spirit of the invention.

What is claimed is:

1. An air conditioning system for a passenger vehicle comprising an air conditioner located in 20 one end of said vehicle, an electric air purifier located in the other end of said vehicle, means for passing outside air into said conditioner, means for passing air recirculated from the passenger 25 space, into said purifier, and a pair of overhead longitudinal ducts arranged alongside each other between said conditioner and said purifier, one of said ducts receiving air from said purifier and discharging same into said conditioner, and the other of said ducts receiving air from said conditioner and discharging same into the passenger space of said vehicle.

2. An air conditioning system for a passenger vehicle comprising an air conditioner located in 35 one end of said vehicle, an electric air purifier located in the other end of said vehicle, means for passing outside air into said conditioner, means for passing air recirculated from the passenger space, into said purifier, a pair of longitudinal ducts, means for passing air from said conditioner 40 into one of said ducts, means for passing air from said purifier through the other of said ducts into said conditioner, and means connecting with the duct from said conditioner for directing the air from said conditioner into the passenger space of 45 said vehicle.
